STOP WATCH ACTUATING DEVICE

George Goda, New York, N.Y., assignor to Clay-Adams, Inc., New York, N.Y., a corporation

Filed Jan. 22, 1962, Ser. No. 68,387

Term of patent 14 years

(Cl. D42—8)

FIG. 1

FIG. 2

FIG. 3

FIG. 4

FIG. 5

FIG. 6

FIG. 1 is a front elevational view of stop watch actuating device showing my new design;

FIG. 2 is a left-side elevational view thereof with the device resting on its inclined base, the opposite side being substantially a mirror image thereof;

FIG. 3 is a rear elevational view thereof taken on the line 3—3 of FIG. 2;

FIG. 4 is a top plan view thereof taken on the line 4—4 of FIG. 2;

FIG. 5 is a bottom plan view thereof; and

FIG. 6 is a sectional view taken on the line 6—6 of FIG. 5.

The broken-line showing of a stop watch in FIG. 1 is for illustrative purposes only.

I claim:

The ornamental design for a stop watch actuating device, substantially as shown and described.
